DESIGN FOR A HAND DUSTER

**Kenneth J. Lewis and Ellsworth S. Bettinger,
San Jose, Calif.**

Application June 7, 1943, Serial No. 110,388

Term of patent 14 years

To all whom it may concern:

Be it known that we, Kenneth J. Lewis and Ellsworth S. Bettinger, both citizens of the United States and residents of San Jose, county of Santa Clara, and State of California, have invented a new, original, and ornamental Design for a Hand Duster, of which the following is a specification, reference being had to the accompanying drawing, forming part thereof.

Figure 1 is a perspective view of a hand duster embodying our new design.

Figure 2 is also a perspective view of said hand duster as viewed from the opposite side of Figure 1.

Figure 3 is a front elevation of said hand duster.

Figure 4 is a plan view thereof.

We claim:

The ornamental design for a hand duster, as shown.

**KENNETH J. LEWIS.
ELLSWORTH S. BETTINGER.**
